NEEDLE FOR MAKING HOOKED RUGS

Vicktor Petterson, Chicago, Ill., assignor, by
mesne assignments, to Fixler Bros., Incorporated,
Chicago, Ill., a corporation of Illinois

Application February 17, 1932. Serial No. 593,540

7 Claims. (Cl. 112—80)

This invention relates in general to an instrument for use in making hooked rugs, and is particularly concerned with a hand operated needle of the shuttle type wherein the spacing of the stitches is accomplished automatically.

It is a primary object of this invention to provide in a needle for making hooked rugs, improved means for operating the needle wherein the handle members are so constructed that they may be easily grasped by the operator and are so designed that the needle may be securely held in operative position and easily guided over the rug pattern as the work of making the hooked rug progresses.

15 It is a further object of this invention to provide in a needle for making hooked rugs, an improved construction in the operating handles and means for connecting them together so that the handles may be easily actuated to move the needle up and down with a shuttle action.

It is a further object of this invention to provide in a shuttle type needle for making hooked rugs, a needle which is so constructed that its course of progress over the rug pattern may be changed without causing damage to the pattern fabric.

25 It is another object of the invention to provide a needle for making hooked rugs which is held in such position during its operation that the operator's view of the rug pattern is not obstructed, whereby the pattern may be more easily and accurately followed, and in which the yarn is fed to the needle at a point above the hands of the operator, rather than below the operator's hands 35 where it would have a tendency to interfere with the work of making the rug.

It is also an object of the invention to provide in an instrument for making hooked rugs, improved means for measuring the loops or stitches.

40 In accordance with the general features of this invention, it is proposed to provide an instrument of the shuttle type for making hooked rugs, wherein the needle and means for measuring the loops or stitches are respectively carried by a pair 45 of mutually connected operating handles. The handles are each constructed of a single metallic strip of material, a portion of each strip being formed into a channel-shaped section which is deflected at one end to form a stop member and 50 bent back upon itself at the other end to form a spaced handle portion and thumb rest which are of such shape as to enable the handles to be easily gripped by the operator's hands and in which the hands are in such position that they are not 55 easily tired from operating the instrument. The

channel-shaped portions of each handle are arranged to interfit and slide relatively to each other. A screw or bolt extends through a slot in one of the channel-shaped portions and engages the channel-shaped portion of the other handle to connect together the handles.

60 Spaced detents or lugs are upset on each channel portion which coact to limit the reciprocal movement of the handles, thus relieving the connecting bolt or screw from shock.

65 A further feature of the invention resides in the provision of a spring member carried by one of the operating handles which is cooperatively associated with the needle carried by the other operating handle. This association of the spring member and needle tends to decrease the pressure of the spring member relatively to the needle at such times as the needle is being withdrawn preparatory to making a new insertion thereof 70 into the pattern fabric, thereby holding the yarn with less pressure.

75 Other objects and features of this invention will more fully appear from the following detail description taken in connection with the accompanying drawings.

80 The accompanying drawings illustrate a needle constructed to embody principles of the present invention, and the views thereof are as follows:

85 Figure 1 is a view showing a hooked rug needle embodying the principles of this invention, and one manner in which it may be grasped by the hands of the operator;

90 Figure 2 is an enlarged vertical sectional view taken through the needle of Figure 1 to show the manner in which the handle operating members are connected for relative reciprocal movement, and also the cooperative relationship between the needle proper and spring follower member for determining the length of loop;

95 Figure 3 is a detailed sectional view showing the relative positions of the spring follower and needle proper, when the needle operating handle is partially raised relatively to the handle carrying the follower;

100 Figure 4 is a horizontal cross-section through the operating handles to show the manner in which the handles are interconnected for relative reciprocal movement, taken substantially on the line IV—IV of Figure 2;

105 Figure 5 is an end view of the illustrated form of needle looking toward the point of the needle;

110 Figure 6 is a view similar to Figure 3 showing the manner of threading the yarn through the needle and against the spring follower and illus-

trates the spring follower as being adjustably supported on the strip;

Figure 7 is a plan view of the follower illustrated in Figures 6, 10 and 11;

5 Figure 8 is an enlarged end view of the point of the needle proper constructed in accordance with the principles of the present invention;

Figure 9 is a view similar to Figure 6 showing the needle proper inserted through the burlap with the spring follower withdrawn;

Figure 10 is a view similar to Figure 9 with the follower retaining the yarn in the burlap during withdrawal of the needle proper; and

Figure 11 is a similar view showing the spring 15 follower still inserted through the burlap and retaining the yarn therein and showing the needle proper as withdrawn from the burlap ready to take the next stitch.

In order that the present invention and its use may be more clearly understood, a brief description of the art of making hooked rugs will be given. A piece of burlap having the rug pattern stamped on one side thereof is tightly stretched over a suitable frame with the stamped side of the burlap disposed so that it will form the wrong side of the rug when completed. By means of a suitable needle through which the desired color of yarn is threaded, the operator successively passes the needle through the burlap to form spaced stitches. This operation results in a loop being formed on the top side of the burlap each time the needle is inserted and withdrawn. These loops should all be of the same length, and when the entire pattern has thus been worked, the loops may be severed at their centers in order to leave a plurality of upstanding strands which form the pattern of the rug.

40 The needle of this invention is of the shuttle type and comprises a pair of mutually connected operating handles which are generally indicated at A and B which respectively carry a follower member 10 and needle 11 which cooperate to carry the yarn through the burlap and determine the length of loop which is formed.

45 The handles A and B are oppositely disposed and each is formed from a single strip of metal. Each strip is formed with an intermediate channel portion 12 as clearly shown in Figures 1, 2, 3, 4 and 5. The lower end of the strip below 50 the channel portion is outwardly deflected to form a presser foot 13 which is provided with a central aperture 14 for a purpose which will be evident subsequently. The upper end of the strip above the channel portion 12 is bent back upon 55 itself to form a short vertical loop 15. From this loop the strip of metal extends outwardly at 16 at substantially right angles to the channel portion 12 to form a thumb rest, and then downwardly to form a handle portion 17 having a 60 curved cross-section. From the handle portion 17 the strip is inwardly deflected at 18 and then downwardly and parallel to the channel portion, as shown at 19. From the parallel portion 19 the strip continues obliquely downwardly as shown 65 at 20, which brings the end of the strip adjacent the presser foot 13 where it is secured to the strip below the channel portion 12 in any well known manner, as by welding, or the like.

It will be observed that the channel portion 12 of the handle A is slightly larger than the channel portion 12 of the handle B, and that these two channel portions of the respective handles are interfitted as shown in Figures 4 and 5 so as to be moved axially relatively to each other. The channel portion 12 of the handle A

is provided with a longitudinally extending slot 21 for receiving therethrough a connecting screw 22 which threadedly engages the channel portion 12 of the handle B. This screw also has threaded thereon a lock nut 23. A washer 24 is disposed underneath the head of the screw 22 to bridge the slot 21.

For limiting the relative reciprocal movement of the channel portions of the handles A and B, one channel portion is provided with a pair of spaced struck-up lugs 25 and 26 which cooperate with a similar pair of lugs on the other channel portion to limit the movement of the channel portions and consequently the relative reciprocal movement of the handles A and B.

The spring follower member 10 is anchored at one end to the strip and extends through an aperture 27 in the strip below the channel portion 12 of the handle A and is secured to the strip in any suitable manner as by welding. Between the anchored end of the resilient member 10 and its free end, which is inwardly deflected as shown at 28, the resilient member 10 is formed with an inwardly projecting portion or hump 29, the purpose of which will subsequently appear.

The needle 11, which is channel shape in cross-section, is secured at its upper end in any appropriate manner, as by welding, to the lower end of the channel portion 12 of the handle B. Just below the presser foot 13 of this handle, the 105 needle is outwardly offset as shown at 30. This offset 30 of the needle results in a shoulder 31 and a body portion 32 which cooperates with the projection or hump 29 on the spring follower member 10 to cause the needle 11 to be shifted laterally during certain portions of the reciprocal 110 movement of the handles A and B relative to each other. The body or shank portion 32 is provided with a transverse aperture 33 which forms the eye of the needle and is disposed above 115 the point 34 of the needle, this point being additionally offset and transversely curved outwardly of the body portion 32 beyond the aperture 33. Since it is common practice in operating an instrument of the type embraced by this invention 120 to reverse the direction in which the needle is progressing by turning the needle while it is still inserted in the burlap fabric pattern, the sides of the needle are rounded as shown at 35. This rounded side portion of the needle extends down- 125 wardly and includes the major portion of the needle point 34. The side walls of the channelled or rounded point of the needle 11 are arcuately curved upwardly to the point or tip of the needle.

The shoulder 31 cooperates with the needle 130 proper 11 to maintain the follower and the needle proper separated so as to not drag the yarn during the time the article is in use. The transverse curve of the point of the needle 11 as well as the arcuate curves of the underside of the side 135 wall of the needle proper enables spreading of the strands of the burlap without cutting and enables the insertion of the needle point in any part of the burlap without cutting. These curved edges and surfaces separate the strands readily 140 and without damage so that the operator may work as fast as desired without damage to the burlap or the finished rug.

Immediately above thumb rest 16 on handle B, there is provided an aperture 36 for receiving the yarn which is indicated as 37 in Figure 1 for making the hooked rug. This yarn is carried to the needle through another aperture 37a which is provided in the angularly disposed portion 20 of the handle B and thence through the aperture 150

14 in the presser foot 13 of this handle and through the eye 33 of the needle. With this arrangement, the yarn is fed to the instrument above the hand of the operator and does not interfere with the guiding of the needle over the pattern design, no matter how the operator grasps the handles A and B.

Another form of spring follower may be employed if desired. Such other form is illustrated 10 in Figures 6, 7, 9 and 11 and comprises a follower of the same general shape as the follower 10 except that the follower 38 is provided with an enlarged head 39 which is bifurcated, forming a slot 40. A screw 41 engages the channel 12 of the handle A and secures the follower 38 in lengthwise adjusted position. The provision of the bifurcated head 39 enables lengthwise adjustment of the follower to vary the length of loops formed in the rug by the present needle.

20 The spring follower 38 is provided with a hump 42 positioned and having the characteristics of the hump 29 of the follower 10.

25 Figure 6 illustrates the yarn 37 interposed between the spring follower 38 and the inside of the needle 11.

30 Figure 9 illustrates the position of the parts after the needle has been passed through the burlap taking with it the yarn 37 which is threaded through the eye 33 of the needle. It will be observed that the strands of the burlap are separated for the needle and the yarn. The operator then pulls down the handle A so that the spring follower 38 lies alongside of the needle 11 and engages and makes the loop C in Figure 35 10. The handle member B is then withdrawn, raising the needle out of the burlap. As the needle is raised the shoulder 31 thereof engages the hump 42 of the spring follower 38 or the hump 29 of the spring follower 10, as the case may be, 40 whereupon the needle is given a movement to the right as viewed in the drawings. This movement will therefore cause the tip of the needle to advance to the right so as to enter between the next pair of strands of the burlap.

45 Figure 11 illustrates the parts after the needle has been withdrawn with the spring follower still at its lowermost position, retaining the loop in the burlap. The operator then actuates the handle B to pass the needle into the space between the next strands of the burlap, and when the needle has been moved downwardly in the position of Figure 9 the handle member A is actuated to withdraw the spring follower. In this manner the needle is operated until the rug is completed.

50 The length of the loop C may be regulated by the lengthwise position of the spring follower 38 with respect to its handle member A, the follower being adjusted by movement of the bifurcated head 39 with respect to the retaining screw 41. 55 The follower 10 which is welded to the handle member A produces loops of uniform length and is not susceptible of adjustment.

60 Briefly, the operation of the needle of this invention for making hooked rugs, is as follows:

65 Having stretched the burlap rug pattern as described above, and threaded the needle as shown in Figure 1, the instrument is grasped by the operator, handle A being grasped by the right hand and handle B by the left hand, when it is desired to have the needle progress toward the left. The handle A is raised relatively to handle B as far as it will go, thus leaving the needle projecting beyond the spring follower member 10. The needle is then inserted through the burlap 75 at a desired point on the pattern and pressed

inwardly until the presser foot above the needle rests on the burlap. Handle A is then moved downwardly until its presser foot rests against the burlap. This movement of handle A causes the deflected end 28 of the spring follower member 10 to follow along the needle until it comes to rest just above the eye 33 thereof. During this movement of the spring follower member 10, the end thereof has contacted with the yarn and determined the length of loop that will be 80 formed when the needle is next raised to its uppermost limit. This raising of the needle to its uppermost limit causes the needle to move upwardly relatively to the yarn which is prevented from moving by its contact with the end of spring 85 follower member 10, and the projection or hump 29 of the follower member moves into the recessed portion 32 of the needle 11, thereby enabling the follower member to move from the position shown in dotted lines in Figure 3 to 90 the full line position as shown therein, this movement being toward the needle.

95 It will now be evident that with the handle B in raised position relatively to handle A, pressure being exerted downwardly on handle A and 100 pressure being exerted upwardly on handle B, there will be a tendency to tilt or rotate the entire instrument against the pressure of the spring follower member 10. This being the case, movement of the handle B downwardly 105 will cause the needle to pass through the pattern fabric at a point in advance of its previous insertion. The needle is moved downwardly until the presser foot of the handle B again strikes the fabric. Handle A is now raised to its uppermost position, which movement releases the 110 spring follower member 10 and enables the same to move over against the needle and pass into the new hole which has been made by the needle. Continuing the operation of the instrument as just described, that is, by alternate up-and-down movement of the handles A and B, the needle progresses along the pattern and produces a series of loops on the under side of the burlap pattern fabric, this under side being the 115 top of the finished rug.

120 From the foregoing, it will be evident that this invention provides a novel needle for making hooked rugs having improved means for operating the needle, this means being so constructed that the handles may be easily grasped by the operator and so designed that the needle will be securely held in operating position and may be easily guided over the pattern which is being worked; in which novel means are provided for connecting the handles together for reciprocal movement, in which the needle is so constructed that it may be turned while it is inserted in the burlap pattern fabric without damaging the fabric; in which the yarn is fed 125 to the instrument in such a manner that it will not interfere with the guiding of the needle over the pattern, and in which improved means are provided for measuring the loops or stitches.

130 The particular construction of the needle 11 135 enables rapid use of the device for making hooked rugs without damage to the fabric and also enables the instrument to be rotated about the axis of the needle proper for turning corners and the like. The instrument travels with an 140 inching movement caused by the hump on the spring follower engaging the shoulder on the needle proper. The adjustment of the spring follower 38, when such is employed, enables the length of the stitches to be adjusted as it has 145

been found that by lengthwise adjusting the spring follower 38 a distance between the tip of the needle 11 and the spring follower varies. Consequently the needle proper may be adjusted to make stitches separated by a single strand of the burlap or by two strands or by three strands, depending of course on the cooperation of the hump and the shoulder.

The formation of the point of the needle is important in that the conversely curved parts separate the strands rather than cutting and the provision of the arcuate under edges of the sides of the needle adjacent its tip enables ready insertion of the needle in the strands of the fabric without tearing or cutting.

The operator may, if desired, grasp the instrument with the thumb against the outside of the thumb portion 16 and the forefinger hooked over this portion with the next finger bearing against the outside of the part 11 in which manner the instrument is operated obliquely to the pattern, thus enabling the operator to more accurately follow the pattern and also being more comfortable for use.

The spring follower 38 when it is adjusted for length in the instrument is guided sidewise by the channel shape of the needle proper 11, and in thuswise is correctly set up in the instrument.

The invention has been described herein more or less precisely as to details, yet it is to be understood that the invention is not to be limited thereby as changes may be made in the arrangement and proportion of parts, and equivalents may be substituted without departing from the spirit and scope of the invention.

I claim as my invention:

1. In a device of the character described, a pair of relatively movable operating handles comprising a channel-shaped member integrally formed with one handle, a channel-shaped member integrally formed with the other handle, said channels being interfittingly associated with the lateral flanges of one channel inside the flanges of the other channel, said second channel having a longitudinally extending slot, a screw extending through said slot in threaded engagement with the first channel, and inwardly struck portions on the respective channels disposed for actively limiting the movement of said channels by said handles.

2. In a device of the character described, a pair of mutually connected operating members, each member being formed from a single strip of metallic material and comprising a channel-shaped portion having an end deflected outwardly to form a stop, the deflected end of one of said members being apertured to form a yarn guide, a handle portion outwardly spaced from the channel portion, said handle portion extending

from the other end of said channel to a point of securement adjacent said first end of the channel member, and a thumb rest at the upper end of the handle portion.

3. In a device of the character described, a pair of operating members connected for relative reciprocal movement, a needle carried by one of said operating members having a laterally offset point, a resilient member having one end anchored on the other operating member and having its free end deflected toward said needle, and means for shifting said deflected end toward and away from said offset end of the needle in response to a movement of said operating members.

4. In a device of the character described, a pair of operating members connected for reciprocal movement, a needle carried by one of said operating members having a lateral offset tip terminating in a point, whereby the spacing between the stitches is determined, the center line of said tip being substantially parallel to the directions of movement of said operating members.

5. In a device of the character described, a pair of operating members connected for reciprocal movement, a needle carried by one of said operating members, said needle having an outwardly offset portion contiguous its point, whereby the spacing between stitches is determined, said offset portion defining a smooth shoulder at its juncture with the shank of the needle.

6. In a device of the character described, a pair of mutually connected operating members each member being formed from a single strip of metallic material and comprising a channel-shaped portion having an end deflected outwardly to form a stop, said deflected end being apertured to form a yarn guide, a hand-grip formed by a straight portion of the strip spaced from the channel portion and parallel thereto, a portion of the strip connecting the lower end of the hand-grip to the channel portion, and a portion of the strip connecting the upper end of the hand-grip to the channel portion, said latter connecting portion being at right angles to the hand-grip portion contiguous its jointure therewith, whereby a thumb rest is formed.

7. A device of the character described, a pair of operating members connected for reciprocal movement, and a needle carried by one of said members, said needle having a shank portion of substantially U-shaped cross-section and an outwardly offset portion contiguous its pointed end, the sides of the shank portion being continued into the offset portion and tapered to define the needle point, the center lines of said portions being substantially parallel.
